UNITED STATES PATENT OFFICE

GEORGE E. STONEBRIDGE, OF NEW YORK, N. Y., ASSIGNOR, BY MESNE ASSIGNMENTS, TO ASSOCIATED ELECTRIC LABORATORIES, INC., OF CHICAGO, ILLINOIS, A CORPORATION OF DELAWARE

LINESWITCH EQUIPMENT

Application filed January 15, 1930. Serial No. 420,848.

This invention relates to improvements in lineswitch equipment, particularly to improvements in plunger type lineswitch equipment, and its object is to make the operation of such switches more reliable by preventing double connections.

The construction, operation, and utility of plunger type lineswitches are too well known to require a detailed discussion here. It is also well known that systems employing these switches are subject to more or less trouble from double connections caused by two or more switches plunging in and seizing the same trunk. Such connections are likely to occur when calls are simultaneously initiated on lines in the same group, and also when one or more calls accumulate during the operation of the master switch. It may be noted that when the master switch is in motion battery is disconnected from the pull-down magnets of all lineswitches of the group, thereby preventing the switches from operating if calls come in at this time. However, in case two or more calls are waiting when the master switch operation ceases and battery is reconnected to the pull-down magnets, the associated lineswitches will plunge in on the same trunk. Such connections are prevented in this present invention by making it possible for only one pull-down magnet circuit to be completed at any one time.

Referring now to the drawing, there is shown a substation A with a line terminating in lineswitch LS, which is one of a group of lineswitches controlled by the master switch MS. The group may comprise twenty-five, fifty, seventy-five or one-hundred lineswitches, groups of this size being most commonly used. Associated with each master switch is one or more distributor switches D through which operating ground is fed to the pull-down magnets of the lineswitches. The distributor switch shown is of the twenty-five point, non-homing, rotary type, although obviously switches of any convenient capacity may be used. In the case of the twenty-five point switch, one or more switches will be required, depending on the size of the group controlled by the master switch. In case a distributor switch of larger

capacity is available, one switch may care for the entire group of lines, although in the larger groups this arrangement has a tendency to slightly delay the extension of calls during the busy period. With either arrangement the possibility of double connection is either entirely eliminated or reduced to a negligible quantity.

To better illustrate the function and utility of the invention the operation of the apparatus involved will now be described in detail. When the receiver is lifted at substation A, a circuit is closed for the line relay 1 of lineswitch LS, which may be traced from battery, winding of relay 1, normally closed contacts 6, line conductor 20, through the loop at the calling substation A, line conductor 19, normally closed contacts 7, common conductor 22, through the winding of relay 3 of the distributor switch D to ground. It will be assumed first that no other lines in the group are calling at this time, and that wiper 30 of the distributor switch stands in the position shown. Relay 1 energizes over the above traced circuit in series with relay 3 which also energizes. Relay 3 connects ground to the common signalling lead at contacts 26, and at contacts 25 closed a circuit from ground, contacts 25, contacts 28, interrupter contacts 29, winding of motor magnet 5, over the common conductor 24, to open main battery at the master switch MS. Magnet 5 energizes over this circuit and opens its own circuit at interrupter contacts 29. The magnet on releasing advances the wiper 30 one step, and again closes its own circuit at interrupter contacts 29. This cycle of operation is repeated and wiper 30 is advanced a step at a time until contact 31 is encountered, at which time a circuit is closed from ground through the winding of relay 4, wiper 30, contact 31, conductor 23, operated contacts 32 of relay 1, through the lower or pull-down winding of the pull-down magnet 2, to open main battery by way of common conductor 24. Relay 4 operates over the above traced circuit and at contacts 28 opens the stepping circuit so that wiper 30 remains in engagement with contact 31. Relay 4 then shunts its own winding by connecting ground

to the above traced circuit at contacts 27, thereby causing the magnet 2 to operate and force the plunger, which is attached to armature 9, into the bank contacts. The cut-off armature 8 is also operated and separates contacts 6 and 7, thereby opening the circuit of relays 1 and 3. Relay 1 is equipped with a copper slug to make it slow releasing and maintains its contacts 32 closed for an interval after its circuit is opened. Relay 4 is also slow acting and maintains the circuit of the pull-down magnet 2, as described, for an interval after the contacts 27 are closed. When the plunger is forced into the banks, the springs 10, 11, and 12 are forced into engagement with contacts 13, 14, and 15, respectively, and the calling line loop is extended over trunk conductors 16 and 18. Release trunk conductor 21 is extended over trunk conductor 17. The trunk comprising conductors 16-18 incidently may terminate in an automatic switch or may extend to an operator's position, in either case the terminating apparatus will be so arranged that when the loop is extended thereto, a holding ground will be returned on conductor 17. The holding winding of magnet 2 will energize from this ground on the release trunk conductor and maintain the plunger of the switch in operated position. Relays 1 and 4 will restore after the necessary delay, and the distributor switch will be available for the next call.

It will be noted that a branch of conductor 17 is extended to the master switch MS. This is in accordance with the usual practice of operating a master switch from ground returned over the release trunk conductor. The master switch operates in the well known way to realign the plungers of the other line switches opposite the next idle trunk in the group, at the same time disconnecting the open main battery from common conductor 24 to prevent the operation of any pull-down magnet, corresponding to magnet 2, or the motor magnet 5 of the distributor switch D and other distributor switches when used, at this time. This arrangement substantially prevents double connections when calls accumulate late in different groups during the master switch operation since the various distributor switches do not start to hunt until the master switch finds an idle trunk.

Conductor 22 leading from relay 3 is common to all lineswitches of the group served by the distributor D. In the event that calls originate on other lines of the group during the operation just described, the relay 3 will be held energized in series with the line relays of the calling lineswitches and will maintain the signalling and stepping circuits previously described. This is without effect, however, until the lineswitch LS is completely operated and the relay 4 deenergized. Relay 4 on restoring again completes the step-

ping circuit for magnet 5, and wiper 30 will be advanced as in the previous instance, until the contact, corresponding to contact 31, of the calling lineswitch is encountered.

It is obvious from the foregoing that regardless of the number of simultaneous calls in the group, or of the number of calls that may accumulate during the operation of the master switch, an operating circuit for only one pull-down magnet will be completed at a time. As the wiper 30 is advanced step-by-step the calling lines will be connected through in succession. Since the operation of the apparatus involved is very rapid, the delay in extending a call will be negligible even during busy periods.

Immediately below the distributor switch D is shown the starting relay 3' of another distributor switch which corresponds in all respects to the switch D but serves a separate group of lines. This additional distributor switch is required only when the line groups are of such size that it is not convenient to serve them with a single distributor switch as shown. Any number of these switches may be provided for a group and will function in exactly the same manner as described for the switch D. The signal common which was shown multiplied to the front contacts of the relay 3 and 3' will take the place of the ordinary supervisory ground signal lead commonly used with plunger lineswitches. This signal lead will extend to a delay device, and in case any of the relays 3 are held operated for an unusual length of time, will operate its signal device to call attention to the condition obtaining.

Having described the invention, what is thought new and is desired to have protected by Letters Patent will be set forth in the appended claims.

What is claimed is:

1. In combination, a plurality of subscriber's individual line switches, an operating magnet for each switch, a normally open circuit for each magnet, and a distributor switch for completing said circuits one at a time.

2. In a combination, a plurality of automatic switches, an operating magnet for each switch, a distributor switch operable under control of any of said automatic switches, contacts accessible to said distributor switch, a circuit for each operating magnet including a separate one of said contacts, and means responsive to any one of said switches being taken into use for operating said distributor switch to connect with the contact associated with said one switch.

3. In combination, a plurality of plunger type lineswitches each having a line relay and a pull-down magnet, a master switch for positioning the lineswitches before idle trunk lines, a distributor switch, and a circuit for the magnet of each lineswitch controlled

jointly by the associated line relay and said distributor switch.

4. In a telephone system, a plurality of non-numerical switches presided over by a common master switch and having access to a plurality of trunk lines, means for operating any switch to connect with an idle trunk line, and a distributor switch for preventing the operation of more than one of said switches at a time.

5. In a telephone system, a plurality of non-numerical switches presided over by a common master switch and having access to a plurality of trunk lines, means responsive to the seizure of one of said non-numerical switches for operating the switch to seize an idle trunk line, and a distributor switch for controlling the operation of said non-numerical switches to prevent the simultaneous seizure of the same trunk line by two non-numerical switches.

6. In a telephone system, a plurality of non-numerical switches presided over by a common master switch and having access to a plurality of trunk lines, a distributor switch having access to said non-numerical switches, means responsive to the seizure of one of said non-numerical switches for operating said distributor to hunt for and connect with the seized non-numerical switch, and means controlled by said distributor for operating the seized switch to connect with an idle trunk line.

7. In a telephone system, a plurality of non-numerical switches presided over by a common master switch and having access to a plurality of trunk lines, means for seizing said switches, a distributor switch for controlling the operation of said non-numerical switches, and means responsive to the seizing of a plurality of said non-numerical switches for causing said distributor switch to operate the seized switches one at a time, whereby, each switch connects with a different trunk line.

8. In a telephone system, a plurality of non-numerical switches each having a line relay and an operating magnet, a distributing device, contacts individual to said non-numerical switches accessible to said device, means for operating the line relay on one of said switches, means responsive to the operation of said line relay for causing said device to engage the contact associated with said one switch, and means responsive to the device engaging said contact for operating the magnet of said one switch.

9. In a telephone system, a plurality of non-numerical switches each having a line relay and an operating magnet, a switching device, a starting relay for said device, contacts individual to said switches accessible to said device, means for operating the line relay of any switch and said starting relay in series responsive to the seizure of a switch,

means responsive to the operation of said starting relay for operating the device into engagement with the contact associated with the seized switch, and means controlled jointly by the line relay of the seized switch and said device for operating the magnet of the seized switch.

10. In a telephone system, a subscriber's line, a non-numerical switch terminating said line, a line relay and an operating magnet for the switch, a finder switch having access to the first switch, means for operating said line relay responsive to the initiation of a call on the line, means controlled by said relay for marking the first switch in the bank of the finder switch, means for operating the finder switch to hunt for and connect with the marked switch, and means controlled by the finder switch for operating the magnet of the switch with which it has connected.

11. In a telephone system, a group of automatic switches, an operating magnet for each switch, a relay for each switch operated responsive to the switch being taken into use to prepare a circuit for the associated magnet, and a distributor switch for completing the prepared circuits successively.

12. In a telephone system, a group of automatic switches having common access to a plurality of trunk lines, a magnet for each switch for effecting a connection with any one of said trunk lines, a relay for each switch operated responsive to the switch being taken into use to prepare a circuit for the associated magnet, and a distributor switch for completing the prepared circuits successively whereby each of the switches connects with a different trunk line.

13. In a telephone system, a group of automatic switches having common access to a group of trunk lines, means responsive to a switch being taken into use for causing the switch to connect with an idle one of said trunk lines, and a distributor switch for preventing more than one switch at a time from operating to connect with a trunk line when a plurality of switches are taken into use simultaneously.

14. The combination comprising a plurality of non-numerical switches having access to a group of trunk lines, a common control switch for positioning said switches in selective relation with an idle one of said trunk lines, and a second common control switch for completing the operating circuits for said first switches successively.

15. The combination comprising a plurality of plunger type lineswitches having common access to a group of trunk lines, a master switch for positioning the lineswitches before an idle one of said trunk lines, a relay for each lineswitch operated responsive to the switch being taken into use, a magnet for each lineswitch for effecting a connection with a trunk line, a distributor switch com-

mon to said lineswitches, and an operating circuit for the magnet of each lineswitch controlled jointly by the associated line relay, said master switch and said distributor switch.

16. The combination comprising a plurality of non-numerical switches presided over by a common master switch for positioning the switches before idle trunk lines accessible thereto; of a distributor switch for preventing the simultaneous operation of two or more of said switches, and circuit connections for preventing the operation of any of said lineswitches or said distributor switch while said master switch is in operation.

17. In a telephone system, a group of non-numerical switches each equipped with an operating magnet, a distributor switch including a wiper adapted to engage contacts individual to each of said first switches, means responsive to any one of said first switches being taken into use for operating the distributor switch to advance said wiper step-by-step over said contacts, and means responsive to said wiper engaging the contact individual to the switch in use for operating the magnet of that switch.

18. In a telephone system, a group of non-numerical switches each equipped with an operating magnet, a distributor switch including a wiper adapted to engage contacts individual to each of said first switches, a circuit completed responsive to any one of said first switches being taken into use for operating the distributor switch to advance said wiper step-by-step over said contacts, and means responsive to said wiper engaging the contact individual to the switch in use for operating the magnet of that switch and for opening said circuit.

In witness whereof, I hereunto subscribe my name this 6th day of January, A. D. 1930.

GEORGE E. STONEBRIDGE.
